UNITED STATES PATENT OFFICE.

GEORGE W. SLANE, OF COLUMBUS, OHIO.

FROGLESS SWITCH.

SPECIFICATION forming part of Letters Patent No. 651,088, dated June 5, 1900.

Application filed March 22, 1900. Serial No. 9,660. (No model.)

To all whom it may concern:

Be it known that I, GEORGE W. SLANE, a citizen of the United States, residing at Columbus, in the county of Franklin and State of Ohio, have invented a certain new and useful Improvement in Frogless Switches, of which the following is a specification.

My invention relates to the improvement of frogless switches; and the objects of my invention are to provide a railway-track with a simple and reliable mechanism whereby the main track may be temporarily made continuous at the usual point of its junction with the switch-rail and whereby said main track may be broken and the switch-rail made continuous therethrough, to provide a shifting rail-section with improved means for operating and supporting the same, to obviate the employment of a frog and guard rails, and to produce other improvements the details of construction of which will be more fully pointed out hereinafter. These objects I accomplish in the manner illustrated in the accompanying drawings, in which—

Figure 1 is a plan view of a portion of a main track and switch-track having my improvement and showing the main track broken. Fig. 2 is a plan view of the shifting or swinging rail supporting plate. Fig. 3 is a side elevation of the same. Fig. 4 is a sectional view on line xx of Fig. 1, and Fig. 5 is a sectional view on line yy of Fig. 1.

Similar numerals refer to similar parts throughout the several views.

1 and 2 represent, respectively, the inner and outer parallel rails of a main track, and 3 and 4 the inner and outer rails of a switch-track, and 5 represents the usual switch-points, which are adapted to be connected in the ordinary manner with the switch-rails 3 and 4.

In carrying out my invention sections of desirable lengths of the main-track rail 2 and switch-rail 3 are removed, and at the center of the space thus formed between the separated rail portions 2 I secure upon one of the ties 6 a plate 7, said plate being provided with a transverse channel 8 on its upper side, which at its central point is equal in width to the width of the base of a track-rail, and from which said central point said channel is formed flaring toward opposite sides of the plate. Within the channel 8 is seated the

base of a swinging track-rail section 9, the latter being adapted when properly turned to fill the space between the ends of the track-rails 2 or ends of the track-rails 3. On opposite sides of the central portion of the rail-section 9 I employ clamping-plates 10, the latter having rounded lateral projections in which are formed vertically-grooved slots 11. Through these slotted openings extend upwardly the upper portions of vertical pins or bolts 12, which rise from the under sides of the plate 7. Between the converging end portions of the rails 2 and 3 I provide filling-blocks 13, these converging rail ends, together with the ends of the rail-section 9, being adapted to bear upon tie-plates 14, which adjacent to the ends of the filling-blocks 13 are formed with shallow upwardly-projecting stop ribs or shoulders 15, against which the bases of the rail-sections 3 and 2 are adapted to abut. With opposite sides of the rail-section 9 and adjacent to the ends thereof are connected the ends of outwardly-extending arms 16, which, as indicated at 17, are jointedly connected with arms 18, the latter having a pivotal connection with the central portions of bars 19, one end of each of said bars being pivoted to a lateral extension of the adjoining plate 14.

20 and 21 represent parallel operating rods or bars which extend in the direction of the length of the ties and which pass beneath the outer track-rail 4. The inner portion of the operating-bar 20 is pivotally connected at 20^a with one end of the bar 19. This operating-bar 20 extends beneath the rail-section 9 and has formed therewith a hook or shoulder termination 22, which engages the outer side of said rail-section 9. The inner side of said rail-section is similarly engaged by a block 23, which is detachably secured to the bar 20. The operating-bar 21 is in a like manner provided with a rigid rail-engaging shoulder 24, corresponding with the shoulder 22, and with a detachable engaging block 25, corresponding with the block 23, while the end of said bar 21 beyond the shoulder 24 is pivotally connected at 21^a with one end of the remaining bar 19.

On the outer side of the outer switch-rail 4 I fulcrum upon convenient ties bell-crank levers 26 and 27, one arm of the lever 26 be-

ing pivotally connected with the outer end of the bar 21 and the corresponding arm of the lever 27 being similarly connected with the outer end of the arm 20. The remaining arms of these bell-cranks are respectively connected with laterally-projecting lugs 28 and 29 of an operating-rod 30, which is movably supported in suitable keepers 31, mounted upon the tie ends. As indicated at 32, I fulcrum on one of the tie extensions opposite the switch-points a bell-crank, one arm of which has a pivotal connection with the outwardly-extending portion of a bar 33, which extends under the switch-rail 4 and is connected with the switch-points 5. The remaining arm of the bell-crank 32 is pivotally connected with the rod 30.

In Fig. 1 of the drawings I have shown the swinging rail-section 9 thrown into alignment with the track-rail sections 3, thereby completing the switch-track across the inner main-track rail. In order to break the switch-rail and close the space between the sections of the main-track rail 2, the rod 30 through the medium of a suitable lever or other operating device is forced in the direction of the arrow, with the result that the rail-section 9 is swung until it is in alignment with the rail-sections 2. It is obvious that a reverse movement of the rod 30 must result in again closing the space between the switch-rail sections 3.

While I have shown herein a swinging-rail section, it will be observed that said rail section is not provided with a central pivot, as is common in constructions of this character, and that the inclined vertical shoulders of the plate 7, which result from the flaring form of the channel in said plate, will operate to limit the swinging movement of the rail-section 9 in either direction. It will also be observed that the swinging rail will be further assured in its position and its movement further limited positively by the pins or bolts which work in the slotted openings 11.

In order to provide against a longitudinal movement of the rail-sections, I have formed

the shallow upwardly-projecting rib 15 on each of the plates 14, this rib not being of sufficient height to interfere with the flanges of car-wheels which pass over the rails or of sufficient width to break the desirable continuity of the rail-sections. Owing to the fact that I have provided a detachable connection of the blocks 25 and 23 with the bars 21 and 20, it will be observed that these blocks 55 may be readily removed, together with the plates 10, to admit of the removal of the rail-section 9.

Through the employment of the mechanism herein described it is obvious that the necessity of employing the usual frog construction is obviated, as well as the necessity of employing guard-rails adjacent to the outer main and switch track rails.

Having now fully described my invention, 65 what I claim, and desire to secure by Letters Patent, is—

In a frogless switch, the combination with the main-track and switch rails, the inner rails thereof being separated at their intersection and a plate supported centrally between the rail-sections, said plate having a transverse channel formed flaring from opposite sides of its center, of a rail-section 9 bearing centrally in said plate-channel, clamping- 70 plates on opposite sides of said rail-section having slotted openings therein, guide-pins projecting from said plate 7 through said slotted openings, outwardly-extending operating-bars engaging said rail-section 9, lever-bars 19 jointedly connecting said operating-bars with rigid ties, jointedly-connected arms between the bars 19 and rail-section 9 and means for imparting a simultaneous outward movement to one of said operating-bars and 85 an inward movement to the other, substantially as specified.

GEORGE W. SLANE.

In presence of—

C. C. SHEPHERD,
A. L. PHELPS.
